Patented May 29, 1917.

FIG. 1.

FIG. 2.

FIG. 3.

FIG. 4.

Inventor
William Hyland
by Herbert W. Jenner,
Attorney.

UNITED STATES PATENT OFFICE.

WILLIAM WYAND, OF ABSECON, NEW JERSEY, ASSIGNOR TO ABSECON MANUFACTURING COMPANY, OF ABSECON, NEW JERSEY.

AIR-MOISTENER.

1,228,157.

Specification of Letters Patent. Patented May 29, 1917.

Application filed March 16, 1916. Serial No. 84,738.

To all whom it may concern:

Be it known that I, WILLIAM WYAND, a citizen of the United States, residing at Absecon, in the county of Atlantic and State 5 of New Jersey, have invented certain new and useful Improvements in Air-Moisteners; and I do hereby declare the following to be a full, clear, and exact description of the invention, such as will enable others 10 skilled in the art to which it appertains to make and use the same.

This invention relates to air moisteners for use in connection with internal combustion engines to moisten the air taken in as 15 a part of the combustible charge; and it consists in the novel construction and combination of the parts hereinafter fully described and claimed.

In the drawings, Figure 1 is a side view 20 of an air moistener constructed according to this invention. Fig. 2 is a vertical section through the air and water valves, and is drawn to a larger scale. Fig. 3 is a plan view of the same. Fig. 4 is a side view of 25 the air moistener showing a modification.

A mixing chamber or pipe 2 is provided, for air and for water in the form of fine spray, and is adapted to be connected to the intake pipe of the engine. This mixing 30 chamber or pipe 2 is preferably passed through a heating chamber 3 which is preferably the exhaust pipe or exhaust manifold of the engine, so that the contents of the mixing chamber may be heated by the waste 35 products of combustion.

A valve casing 4 is provided, and is divided into two chambers by a diaphragm 5 of flexible material. The upper chamber 6, above the diaphragm, is an air chamber, and 40 the lower chamber 7 is adapted to hold water or other approved moistening fluid.

The lower chamber 7 has a water inlet pipe 8 connected to it, and 9 is a valve of any approved sort for drawing off the water from the chamber when desirable. The 45 lower chamber has an outlet 10 for water at its bottom, and 12 is a needle valve which operates as a spray-forming device, and which controls the passage of water through 50 the outlet 10.

The stem 14 of the needle valve is secured in a metal disk 19 which is attached to the center part of the diaphragm. The upper end portion of the valve stem 14 works in a 55 guide 15 secured to the top of the casing.

The guide is screwed in the top of the casing so that its position can be adjusted, and 60 16 is a jam nut for locking it in place. A helical spring 17 is arranged in the guide between the guide and the disk 19 so that the needle valve is pressed toward its seat and normally closes the outlet. The tension of the spring 17 is varied by adjusting the position of the guide. A stop stem 20 is provided and is screwed into the top end of the 65 guide, and this stop stem projects downwardly so that the upper end of the stem of the needle valve may strike it. The stem 20 is adjusted to vary the lift of the needle valve, or to hold it closed, if necessary. A helical spring 21 is arranged between the 70 top of the guide and the head 22 of the stop stem to prevent the accidental displacement of the stem.

A tubular connecting-piece or air-inlet piece 24 is arranged between the lower part of the casing 4 and the mixing chamber, and is suitably secured to the said parts. Two large inlet openings 25 for air are formed 80 in the middle part of the connecting-piece 24, upon opposite sides of it, and these openings form sight-holes through which the feed of water from the needle valve may be clearly seen. The connecting-piece has an 85 inlet valve 26 which opens downwardly or inwardly toward the mixing chamber. This valve 26 is arranged below the level of the holes 25, and it is normally held to its seat by a light spring 27.

The air space of the upper chamber 6 is connected with the mixing chamber and with the intake of the engine by means of a pipe 30. In the form of the device shown in Fig. 1, this pipe 30 is shown connected to 95 the mixing chamber or pipe after it has passed through the exhaust or heating pipe, and where the suction of the intake is considerable. In the form of the device shown in Fig. 4, the pipe 130 is connected with the mixing chamber or pipe before it enters the exhaust pipe, and where the suction of the intake is less. This device however is more compact and the air pipe is shorter, than in the device shown in Fig. 1.

When the engine is at work, the suction of its intake at each outstroke of its piston during which a charge is drawn into its cylinder, reduces the pressure in the air chamber 6 below that of the atmosphere, and thereby 110

causes the flexible diaphragm to move upwardly and open the needle valve. The water rushes through the needle valve and is projected in the form of spray through the inlet valve 26 into the mixing chamber. The valve 26 is opened simultaneously with the opening of the needle valve, as the pressure in the mixing chamber is also reduced below that of the atmosphere, and the air rushes through the inlet holes 25 and the valve 26, and becomes mixed with the spray in the mixing chamber.

The heat of the exhaust pipe vaporizes parts of the fine spray, and also retards the formation of large drops of moisture and vaporizes any drops which may be formed and which fall to the bottom of the mixing chamber. This enables the air to carry a large supply of moisture with it into the engine cylinder.

This moisture prevents the formation of solid deposits of carbon in the engine cylinder, which would greatly interfere with the satisfactory working of the engine. When the engine is not at work, and when its cylinder is not drawing in a new charge, the action of the moistener is suspended, as the water valve is not opened.

What I claim is:

- 30 1. In an air moistener, a mixing chamber, an inlet valve for the said chamber, a water valve, and an air-inlet piece secured between the said inlet valve and water valve, said valves both being operated automatically and independently of each other when the pressure in the mixing chamber is reduced, and the said water valve operating to feed the water through the air-inlet piece and inlet valve into the mixing chamber.
- 40 2. In an air moistener, a mixing chamber, an inlet valve for the said chamber, a water valve, and an air-inlet piece secured between the said inlet valve and water valve and having air inlet openings at opposite sides of it which form sight-holes for the feed from the water valve through the said inlet valve into the mixing chamber, said valves being operated automatically and in-

dependently of each other when the pressure in the mixing chamber is reduced.

3. In an air moistener, a mixing chamber, an inlet valve for the mixing chamber, a casing, a diaphragm secured in the casing and separating it into a water chamber and an air chamber, a water valve controlled by the said diaphragm and operatively connected with the said mixing chamber, and a pipe connection between the said air chamber and the mixing chamber, whereby the said inlet valve and water valve are opened simultaneously when the pressure in the mixing chamber is reduced below that of the atmosphere.

4. In an air moistener, a mixing chamber, an inlet valve for the said chamber, a water valve, and an air-inlet piece secured between the said inlet valve and water valve and provided with a sight-hole for the feed from the water valve, said inlet valve and water valve being operated automatically when the pressure in the mixing chamber is reduced below that of the atmosphere.

5. In an air moistener, a mixing chamber, an inlet valve for the mixing chamber, a casing, a flexible diaphragm secured in the casing and separating it into a water chamber and an air chamber, a water valve controlled by the said diaphragm and discharging into the mixing chamber, a spring normally closing the said water valve, a stop for regulating the lift of the said water valve, and a pipe connection between the air chamber and the mixing chamber.

6. In an air moistener, a mixing chamber, an inlet valve for the mixing chamber, a casing, a diaphragm secured in the casing and separating it into a water chamber and an air chamber, a water valve controlled by the said diaphragm and operatively connected with the said mixing chamber, and a pipe connection secured to the said air chamber and operatively connected with the delivery end portion of the said mixing chamber.

In testimony whereof I have affixed my signature.

WILLIAM WYAND.
